FLUID PRESSURE OPERATED JACK

Sydney Macdonald Parker, Myton, England, assignor to Automotive Products Company Limited, London, England

Application November 10, 1937, Serial No. 173,928
In Great Britain November 11, 1936

13 Claims. (Cl. 121—40)

The invention relates to fluid pressure actuated jacks, adapted to be used for operating retractable undercarriages, bomb release gear of aircraft and the like, and provided with locking mechanism acting to retain the jack in either or both of its extreme positions.

In certain cases when a relatively rigid structure is used, more than one jack is employed to operate the undercarriage unit or other operated element, and in such cases it is desirable that all the jacks should work together, and in particular that no one of the jacks should commence to operate, i. e. extend or contract as the case may be, until all the jacks are unlocked.

15 A risk of distorting or jamming the undercarriage in the event of one of the locking means being stiffer than the other or others, is thus avoided.

One object of the present invention is to provide a system which will prevent any one of a series of jacks from operating until all of the series are unlocked.

Another object of the invention is to provide a fluid actuated system having a plurality of 25 jacks each of which is provided with individual locking means adapted to be released by the pressure fluid fed to the jack, and including a valve device which prevents any one of said jacks from being operated until the locking means of 30 all the jacks are released.

Another object of the invention is to provide a fluid actuated system having a plurality of jacks to be extended and contracted in unison, each having individual locking means released by the pressure fluid fed to the jack, and including a valve device on each of the jacks to arrest the flow of fluid to the jack when the locking means thereof has been released and to lead said fluid to another of the jacks.

40 A further object of the invention is to provide a fluid actuated system including a pair of jacks to be operated in unison and each fitted with individual locking means released by the pressure fluid, and including a valve device interposed between each jack and the source of pressure fluid, said valve device being actuated by the locking means of the corresponding jack for leading the pressure fluid to the working space of the other jack when the locking means of the said corresponding jack has been released.

Yet another object of the invention is to provide a fluid actuated system comprising a pair of jacks to be operated in unison from a common source of fluid pressure, each fitted with locking means released by the said pressure, and includ-

ing a changeover valve device actuated by the respective locking means to prevent either jack from being operated until both locking means are released, each of said changeover valve devices having a main pipe connection fed with pressure fluid from the source and being adapted to lead fluid from this main connection, to the corresponding lock-releasing means when the locking means is in action, or to the working space of the other jack of the pair when the said locking means is released.

Other objects and features of the invention and other novel combinations of parts and desirable particular constructions will be apparent from the following description and from the accompanying drawings, in which

Figure 1 is a diagram indicating a general arrangement used for inter-connecting a pair of jacks having external fluid actuated locking devices;

Figure 2 is a sectional fragmentary elevation through the end of a jack to show a constructional form where the valve device is actuated by an internal lock;

Figure 3 is a fragmentary sectional elevation corresponding to Figure 2 but with the valve device in the position corresponding to the unlocked state of the jack; and

Figure 4 is a diagram illustrating a modification enabling more than two jacks to be interlocked.

In the example shown in Figure 1 a pair of jack units 10 and 11, such for example as are commonly employed for operating a retractable aircraft undercarriage, are arranged side by side, and have plunger members 12 and 13 respectively adapted to be forced down by fluid pressure introduced through pipe connections 14 and 15 in order to extend the jack and to move upwardly by passing fluid under pressure through the connections 16 and 17 when the jack is required to be contracted or shortened.

In order that the jacks may be positively held in their fully closed condition each of the plungers 12 and 13 is formed with a flange 18 which is adapted to be engaged by the turned in extremities 19 of a pair of locking levers 20, these being pivoted upon lugs 21 as indicated at 22. At its upper end each of the levers 20 is formed with a slot 23, and these are connected by a sliding pin 24 with a rod 25 secured to a piston 26 disposed within a hydraulic cylinder 27. A spring 28 normally urges the piston 26 in an upward direction and consequently causes the levers 20

20

25

30

35

40

45

50

55

to lock the plunger 12 mechanically when it is disposed in its uppermost position.

The cylinder 27 is extended to form the casing of a valve device 29 having a fixed seating 30, 5 which is engaged by the head 31 of a mushroom valve element when the piston 26 is moved to its lowermost position during the process of releasing the locking levers 20, the stem 32 of said valve element being adapted to engage the piston 26. The valve element 31, 32 is hollow and is arranged to accommodate slidably the stem 33 of a second mushroom valve element having a head portion 34 adapted to engage a fixed seating 35 by the action of a coiled compression 10 spring 36 tending to force apart the two heads 31 and 34. A further coiled compression spring 37 acts between the head 31 and the end of the casing 29 so as to keep the stem 32 in firm contact with the piston 26. The movement of the 15 stem 33 within the valve element 31, 32 is limited by a pin 38 which is secured to the head 31 and passes through a slot 39 in the stem 33. As the piston 26 is moved downwardly by pressure fluid, as will be hereinafter explained, the spring 37 causes the valve element 31, 32 to follow, while the spring 36 firmly holds the head 34 of the 20 second valve element in contact with the seating 35. Just before the head 31 reaches the fixed seating 30, however, the pin 38 contacts with the 25 lower end of the slot 39, and thus the final movement of the valve element 31, 32 closes the seating 30 and at the same time causes the head 34 to leave the seating 35. A valve device of identical construction is fitted to the jack 11 and is indicated generally at 29a.

The system as a whole is a double-acting one and is supplied with fluid under pressure to a pipe connection 40 in order to unlock and lower the two plungers 12 and 13 while pressure fluid 40 fed into the opposite pipe connection 41 correspondingly raises the plungers 12 and 13 until they automatically become locked, a sloping surface 42 on each plunger being arranged to slide past oblique surfaces 43 on the locking levers 20 until such time as the latter are free to move inwardly and hold the plunger in a locked condition. The action of the valve devices 29, 29a in accordance with the invention is as follows. When pressure fluid is fed into the connection 40 it passes into spaces 44 and 44a in the respective valve devices by way of main connections 45 and 45a. Both jacks being locked, the valve elements are in the positions shown in Figure 1, and therefore the fluid passes through the valve seatings 30, 30a and presses downwardly the two pistons 26 and 26a, thus moving outwardly the lower ends 19 of the locking levers 20. At the moment when the plungers 12 and 13 are free the heads 31 and 31a reach the fixed seatings 30 and 30a so that the supply of fluid from the main connection 45 is transferred past the seating 35 to a pipe 46 which leads to the jack connection 15, thus enabling said fluid to extend the jack 11. Similarly the fluid fed through the main connection 45a passes through a pipe connection 46a and has the effect of extending the jack 10. In the event of say the jack 10 becoming unlocked prior to the jack 11 it will be seen that the fluid from the main connection 45 is transferred by the opening of the valve seat 35 to a pipe 41a which enables the pressure fluid from the valve device 29 to act upon the piston 26a until such time as this piston has completed its movement. At the same time pressure fluid is fed to the connection 15, but, of course, it cannot effect the

extension of the jack 11 until the corresponding locking means have been released. Thus, the two valve devices 29, 29a act as change-over valves, and each feeds either the corresponding locking means or else the other jack according to the position occupied by the valve elements.

A constructional embodiment of the invention as incorporated in a jack unit of the type disclosed in the United States Patent to Francis Victor Brown No. 2,074,772, issued on March 23rd, 1937, is shown in Figures 2 and 3. The valve devices 29, 29a which are identical in construction to those shown in Figure 1, are in this case incorporated in the respective cylinder heads indicated at 50 and 50a, and the stem 32 of the lower valve element is engaged and is controlled by a cam or spade member 51 associated with the locking means of the jack. The operation of these locking means will be clear from the aforementioned United States Patent No. 2,074,772, but said means comprises briefly a pair of radially slidable detents, one of which is shown at 52, and which are notched to engage projections 53 formed upon a pair of extensions or ears 54 carried by the plunger element of the jack. The spade member 51 which is connected with the extensions 54 and the plunger by a lost motion device (not shown) is moved downwardly when pressure fluid is introduced into the space 55 within the jack, and as said spade member is formed with sloping cam surfaces on its front and rear edges when viewed as in Figure 2, this downward movement causes the detent plungers 52 to be pressed outwardly, thus releasing the plunger of the jack. It will be seen that this downward movement of the spade member 51 also causes the change-over valve device 29 to be actuated, and this device is so arranged that when the locking means is fully released the valve seating 30 is closed and the valve seating 35 opened. The internal construction of the jack 11 is identical, and is therefore merely indicated diagrammatically to a small scale in Figure 2 so as to show the pipe connections.

As before, pressure fluid for extending the jacks 10 and 11 is introduced through main connections 45 and 45a simultaneously, and in the case of the jack 10 this fluid initially passes by way of the valve seat 30 into the space 55, thus releasing the locking means and moving the spade member 51 downwardly. When the locking means are completely released the valve seat 30 becomes closed (as seen in Figure 3), and the pressure fluid from the main connection 45 therefore passes by way of the connection 46 to the connection 14a of the other jack 11. It will be realized that if the locking means of this jack have not been fully released the pressure fluid passing through the connection 14a into the space 55a will assist the unlocking operation. In the meantime the supply of pressure fluid to the jack 10 is cut off, but when the release of the locking means in the jack 11 is completed the pressure fluid from the main connection 45a then passes through the pipe 46a and enters the cylinder 65 of the jack 10 by way of the connection 14.

The method of controlling the input of fluid pressure to the jacks so as to make sure that all of said jacks are unlocked before any is allowed to extend (or contract as the case may be) may also be applied to instances where a common source of fluid pressure is used to actuate more than two jacks, and a system embodying four of these jacks requiring simultaneous operation is illustrated diagrammatically in Figure 4. As 75

shown, the jacks are associated in pairs and are indicated at 10, 11 and 10a, 11a, the input of pressure fluid from a pipe connection 61 to the unlocking means of the jacks 10 and 11 being controlled by an auxiliary valve device indicated at 68, while a similar valve device 68a is associated with the two jacks 10a and 11a. The locking means of the four jacks are the same as those shown in Figure 1, and comprise pairs of levers 20 adapted to hold the plunger members 12, 13 and 12a, 13a in their fully raised positions, said levers 20 being actuated by valve devices 62, 63 and 62a, 63a, all identical in construction with the valve devices 28, 29a shown in Figure 1. For actuating the auxiliary valve devices 68 and 68a however, transverse links 64, 64a are carried by the stems 25 and 25a respectively and are connected at their middle points with push rods 65, 65a. The lower end of each of these rods passes 20 slidably through the casing of the corresponding auxiliary valve 68 or 68a and is arranged to operate a corresponding valve element 66 or 66a. At its upper end this has a mushroom head 67 or 67a which when depressed mates with a seating 68 or 68a, while the lower end of the stem 66 or 66a has a smaller head 69 or 69a. The stems 66 and 66a are pressed upwardly by coiled compression springs 70 and 70a so as to occupy the positions shown when the locking means of the jacks 30 are all operative. Thus when pressure fluid is fed through the connection 61 it is allowed to pass to the connection 40 feeding the valve devices 62 and 63 of the jacks 10 and 11, while the fact that the head 67a of the valve 68a is off its seating 68a enables the pressure fluid similarly to reach the pipe connection 40a feeding the valve devices 62a and 63a of the jacks 10a and 11a respectively. The action in each pair of jacks is thus exactly the same as that previously described in connection with the arrangement shown in Figure 1, the release of both locking means of any one pair of jacks causing the centre part of the corresponding link 64 or 64a to be moved downwardly sufficient to close the valve seating 68 or 68a and upon the corresponding passage past the head of the valve member 69 or 69a in the auxiliary valves. Assuming that the two jacks 10 and 11 become unlocked before the jacks 10a and 11a this will mean that the supply of fluid through the pipe connection 40 is cut off and the feed through the pipe 61 therefore passes through a connection 71 leading to the connection 40a, which latter it will be seen is already connected with the supply 61 by way of the valve seating 68a. Thus, the whole 55 of the fluid pressure is concentrated upon unlocking the jacks 10a and 11a, and when this has been effected the consequent lowering of the centre part of the link 64a causes the valve seating 68a to be closed and the passage past the valve head 69a to be opened. This action enables fluid from the pipe connection 61 to pass the valve member 68a and thus reach the pipe connection 40, from which latter it flows into the valve devices 62 and 63 and thence to the cylinder connections 14 and 15, since the unlocking of the plungers 12 and 13 has already opened the valve seating 35 in the manner previously explained. The jacks illustrated are double-acting ones, and the fluid pressure used for closing or shortening them is supplied through a connection 41 having branches connected to the respective cylinders at 16, 17, 16a and 17a.

Various modifications may, of course, be made in the arrangements described, and the principle shown in Figure 4 may be extended to embrace

any number of jacks operated from a common source of pressure fluid. In cases where the jack is locked in its completely extended position the same general arrangements can be used, except, of course, that the pipe connections 14 and 15 to the jack cylinders would be interchanged with the connections 16 and 17 respectively, suitable modification being made in the mechanical details of the locking mechanism. In some cases it may be desirable for the plungers to be locked at each extreme position, and for this purpose the interlocking valve systems shown can be duplicated.

Although this invention has been described in connection with certain specific embodiments, the principles involved are susceptible of numerous other applications that will readily occur to persons skilled in the art. The invention is, therefore, to be limited only as indicated by the scope of the appended claims.

Having thus described the various features of the invention, what I claim as new and desire to secure by Letters Patent is,—

1. A fluid operated system including a plurality of fluid operated jacks, a locking means for each jack, means for releasing the locking means by pressure fluid, said releasing means including a feed line individual to each jack and its locking means and a valve device in each of said individual feed lines preventing any of said jacks from being operated until the locking means of all the jacks are released.

2. A fluid operated system including a plurality of fluid operated jacks, a locking means for each jack, means for releasing the locking means by pressure fluid fed to the jack, and a valve device associated with each of said jacks for arresting the flow of fluid to the jack when the locking means thereof has been released and leading said fluid to another of the jacks.

3. A fluid operated system including a source of fluid pressure, a plurality of fluid operated jacks, a locking means for each jack, a valve device interposed between each jack and the source of pressure fluid, means for releasing the locking means actuated by pressure fluid fed to the valve, and means for stopping the flow of fluid to the lock releasing means of one jack and directing said fluid to the lock releasing means of another jack.

4. A fluid operated system including a source of fluid pressure, a plurality of jacks each having a working chamber, a locking means for each jack, means for releasing the locking means by pressure fluid fed to the working chamber of the jack, and a valve device associated with each of said jacks for arresting the flow of fluid to the jack when the locking thereof has been released and leading said fluid to the lock releasing means and the working chamber of another jack.

5. A fluid operated system including a source of pressure fluid, a plurality of jacks each having a working chamber, a locking means for each jack, means for releasing the locking means by pressure fluid fed to the jack, a change-over valve device interposed between each jack and the source of pressure fluid, means for directing the flow of fluid to the lock releasing means and to the working chamber of one jack in one position of the valve device, and means for stopping the flow of fluid to said jack in another position of the valve device and directing said fluid to the lock releasing means and the working chamber of another jack.

6. A fluid operated system including a source

- of pressure fluid, a plurality of fluid operated jacks, a locking means for each jack, means for releasing the locking means by pressure fluid fed to the jack, a valve device interposed between each jack and the source of pressure fluid, a valve member in said valve device controlling the flow of fluid to the lock releasing means of one jack and which is disengaged from its seat when said lock releasing means is in operative position, another valve member interconnected with the first valve member by a lost motion connection and which controls the flow of fluid to the lock releasing means of another jack, said second valve member being engaged with its seat when the lock releasing means of the first jack is in operative position.
7. A fluid operated system according to claim 6 including a mushroom valve member controlling the flow of fluid to the lock releasing means of one jack, a bore in said valve member, a mushroom valve member controlling the flow of fluid to the lock releasing means of another jack, a stem extending from the second valve member and located in the said bore, and yielding means for spreading said valve members one from another.
8. A fluid operated system including a plurality of fluid operated jacks, a locking means for each jack, fluid operated means for releasing the locking means of one jack, fluid operated means for releasing the locking means of another jack, and a two-stage valve means for controlling the operation of said lock releasing means, the second stage of valve operation being in response to the release of the locking means for one jack, and serving to direct the fluid flow away from said first named releasing means, and toward the second named releasing means.
9. A fluid operated system including a source of fluid pressure, a plurality of fluid operated jacks each including a working chamber, a locking means for each jack, means for releasing the locking means by pressure fluid fed to the jack, a two-position valve, means connecting the source of pressure fluid to the lock releasing means and the working chamber of the jacks in one position of the valve, and means for disconnecting the lock releasing means and the working chamber of one jack and directing the pressure fluid to the other jack in the other position of the valve.
10. A fluid operated system including a plurality of fluid operated jacks, a locking means for each jack, means for releasing the locking means by pressure fluid fed to the jack, a valve device associated with one releasing means for arresting the flow of pressure fluid to said releasing means and leading the pressure fluid to another releasing means.
11. A fluid operated system including two sets of jacks, each set having a working chamber for each jack, and a locking means for each jack, means for releasing the locking means by pressure fluid fed to the jacks, a valve device associated with one set of jacks, an operative connection between the locking means of said set of jacks and the said valve device adapted to stop the flow of pressure fluid to the lock releasing means of said set of jacks and lead said pressure fluid to the lock releasing means and to the working chambers of the other set of jacks, a valve device associated with said other set of jacks, an operative connection between the locking means of said other set of jacks and the second valve device adapted to stop the flow of fluid to the lock releasing means of the second set of jacks and leading said pressure fluid to the lock releasing means and to the working chambers of the first set of jacks.
12. A fluid operated system including a plurality of jacks and a locking means for each jack, means for releasing the locking means by pressure fluid fed to the jack, a valve device associated with each of said jacks for arresting the flow of fluid to the jack when the locking means thereof has been released, and for leading said fluid to another of the jacks, and means for independently holding one of said valve devices in position to arrest flow to the associated jack and jack releasing means, said holding means being operative upon release of the locking means for said jack.
13. A fluid operated system including a plurality of jacks and a locking means for each jack, means for releasing the locking means by pressure fluid fed to the jack, a valve device associated with each of said jacks for arresting the flow of fluid to the jack when the locking means thereof has been released, and for leading said fluid to another of the jacks, and resilient means for independently holding one of said valve devices in position to arrest flow to the associated jack and jack releasing means, said resilient means being operative upon release of the locking means for said jack.

SIDNEY MACDONALD PARKER.
